(57) **CLAIM**

The ornamental design for a forearm-gripping stabilizing attachment, as shown and described.

DESCRIPTION

FIG. 1 is a front perspective the forearm-gripping stabilizing attachment;

FIG. 2 is a rear perspective view of the forearm-gripping stabilizing attachment;

FIG. 3 is a front elevation view of the forearm-gripping stabilizing attachment;

FIG. 4 is a rear elevation view of the forearm-gripping stabilizing attachment;

FIG. 5 is a side elevation view of the forearm-gripping stabilizing attachment, the opposite side being a mirror image;

FIG. 6 is a top plan view of the forearm-gripping stabilizing attachment; and,

FIG. 7 is a bottom plan view the forearm-gripping stabilizing. The broken lines in FIGS. 1 through 7 are environmental structure only and form no part of the claimed design.
